UNITED STATES PATENT OFFICE.

RALPH R. ROOT, OF LAKEWOOD, OHIO, ASSIGNOR TO THE GLOBE MACHINE AND STAMPING COMPANY, OF CLEVELAND, OHIO, A CORPORATION OF OHIO.

DESIGN FOR A GLASS FACE FOR A TAIL LAMP.

Application filed December 16, 1921. Serial No. 522,923. Term of patent 7 years.

To all whom it may concern:

Be it known that I, RALPH R. Root, a citizen of the United States, residing at Lakewood, in the county of Cuyahoga and State of Ohio, have invented a new, original, and ornamental Design for Glass Face for a Tail Lamp, of which the following is a specification, reference being had to the accompanying drawing, forming part thereof.

In said drawing, Fig. 1 is a front elevation and Fig. 2 is a side elevation of a glass face for a tail lamp showing my new design.

I claim:

The ornamental design for glass face for a tail lamp, as shown.

RALPH R. ROOT.
